MINERAL WOOL FORMING APPARATUS

Nicholas Dobak, Manville, and Edward R. Powell,
North Plainfield, N. J., assignors to Johns-Manville Corporation, New York, N. Y., a corporation of New York

Application May 21, 1941, Serial No. 394,506

10 Claims.

(Cl. 83—91)

The present invention relates to improvements in fluid jet nozzles employed in the manufacture of mineral wool for shredding a molten stream of the raw mineral wool forming material into fibres.

At the present time it is conventional in the art to subject a molten stream of slag, or the like, to the shredding action of a blast of steam or other fluid issuing from a nozzle located adjacent the stream. Various types of nozzles have been employed for this purpose, none of which have proven successful in converting a desirably high proportion of the molten stream into fibres with a minimum of unfiberized particles or shot. The instant invention has for its principal object the provision of an improved nozzle which produces in operation an increased fibre yield.

Another object of the invention is the provision of a nozzle of the type referred to, which is constructed to focus the main force of divergent steam jets substantially on a line parallel to and spaced from the forward face of the nozzle to obtain an improved shredding action.

A further object of the invention is the provision of means to secure an improved relationship between the nozzle and the molten stream.

Our invention will be more fully understood and further objects and advantages thereof will become apparent when reference is made to the more detailed description thereof which is to follow and to the accompanying drawings, in which:

Fig. 1 is a side view illustrating portions of a mineral wool forming apparatus and nozzle of the instant invention in position for operation;

Fig. 2 is a front view of the apparatus of Fig. 1;

Fig. 3 is an enlarged front view of a nozzle in accordance with the instant invention;

Fig. 4 is a sectional view taken on the line 4—4 of Fig. 3;

Fig. 5 is a fragmentary sectional view taken on the line 5—5 of Fig. 4;

Fig. 6 is a sectional view taken on the line 6—6 of Fig. 4;

Fig. 7 is a top plan view of the nozzle of Fig. 3;

Fig. 8 is a sectional view taken on the line 8—8 of Fig. 3;

Fig. 9 is a perspective view of the nozzle of the instant invention, illustrating its operation in conjunction with the stream of molten material;

Fig. 10 is a view looking downward upon the nozzle of Fig. 9;

Fig. 11 is a front view of a modified form of nozzle;

Fig. 12 is a sectional view taken on the line 12—12 of Fig. 11;

Fig. 13 is a plan view of the nozzle of Fig. 11; and

Fig. 14 is a sectional view taken on the line 14—14 of Fig. 11.

Referring now to the drawings, and particularly to Figs. 1 and 2, a mineral wool forming apparatus is disclosed, comprising a furnace 10 for melting the slag, rock, or the like, to be converted into mineral wool fibres. Furnace 10 may be a cupola, such as conventionally employed in the art, a tank furnace, or the like. A stream of molten mineral wool forming material may be discharged from the furnace to a stream splitter, or the like, illustrated diagrammatically at 12, and from thence in front of and adjacent to a shredding nozzle 14 where it is shredded into a great multiplicity of fine fibres and some proportion of unfiberized particles or shot by a fluid blast, suitably high pressure steam or compressed air, issuing from the nozzle.

In accordance with the instant invention, nozzle 14 comprises a hollow body (see Figs. 3 to 8, inclusive), preferably formed as a single casting. The lower portion of the body includes an interiorly threaded collar 16 adapted to receive the end of a nipple, or the like, 18, forming part of a line 19 in communication with some suitable source of fluid under pressure, such as steam or compressed air.

The nozzle is preferably formed to include two upstanding sections or wings 20 and 22, respectively, the adjacent inner walls of which upwardly diverge in substantially a V-shape. The outer walls, as seen in front view in Fig. 3, are suitably substantially parallel, as shown, but converge upwardly, in side view as shown in Fig. 4. The walls of the hollow body are of a thickness to withstand the fluid pressures employed, and the walls defining the inner sides of the wings are joined and extended, as indicated at 24, to divide the interior of the body into two separate chambers, 26 and 28. Each wing 20 and 22 includes an elongated discharge orifice 30 formed by preferably parallel-sided slots communicating with the hollow interiors of the wings and through which the steam, compressed air, or other fluid, issues as a high velocity jet to perform the shredding operation. The orifices 30 upwardly diverge and may lie in substantial parallelism to the adjacent walls of the respective wings to form together a substantially V-shaped fluid discharge port.

Referring now particularly to Figs. 4, 6, 7, and 55 8, a particular feature of the invention is dis-

closed, comprising an offset arrangement of the face portions of the nozzle adjacent the orifices. That is, a shoulder 32 is formed which lies in the plane of the outer wall of the slot defining an orifice and extends the length of each orifice and is in alignment with its outer edge. The shoulder tapers from a minimum height at or adjacent the lower terminal of the orifice to an increased height at or adjacent its upper terminal. The shoulder is suitably formed by removing a portion of the metal forming the forward face of the nozzle adjacent the inner walls of the slot as by machining, or the like. Such finished inner faces 34, after the machining operation, preferably lie in a plane substantially at right angles, or in a plane at greater than a right angle, to the plane of the abutment or shoulder 32.

Referring now to Figs. 9 and 10, the operation of the nozzle in conjunction with a stream of the molten material is illustrated. The nozzle in Fig. 9, as well as in Fig. 9, as well as in Figs. 3, 4, and 5, is shown in a vertical position, with the stream falling at an angle considerably different from the normal case for purposes of clarity in illustration. However, as illustrated in Fig. 2, the nozzle, when in use, is so disposed that one of the orifices 30 extends in a direction substantially parallel to the stream 36 of molten material.

Steam or other fluid is supplied to the nozzle through line 19 and issues from orifices 30 making up the V-shaped fluid discharge port. Shoulders 32 force the steam or other fluid under pressure to expand in an inward direction, the degree of divergence of the jets from their normal courses depending upon the height of the shoulders. Consequently, the gradual increase in the heights of shoulders 32 causes a like gradual increase in the divergence of the jets to produce the effect illustrated in Figs. 9 and 10, in which the main paths of movement of the jets are indicated by the finer dash lines. The stream of molten material 36, falling between the jets as illustrated, and closely adjacent and substantially parallel to one of the orifices, is completely surrounded by the steam and shredded into a great multiplicity of extremely fine fibres, the shredding action being illustrated by the heavy dash lines in Figs. 9 and 10.

It has been determined that the nozzle of the instant invention, employed as described above, produces a substantially increased yield of fibres, with a corresponding reduction in the amount of unfiberized particles or shot as compared to jet arrangements heretofore employed. As will be readily appreciated, the greater the proportion of material that is converted into fibres, the greater the savings obtained; and also, and as a matter of particular importance, the reduction in the amount of shot contained in the mineral wool greatly enhances the value of the finished product.

Referring now to Figs. 11 to 14, inclusive, a somewhat modified form of the invention is disclosed. In this embodiment, the hollow body includes an integral casting similar to that previously described, but without walls for the inner sides of the wings, the wings in this instance being indicated by the reference characters 48 and 42. In place of the integrally cast inner walls of the previous embodiment, separate plates 44 are employed, formed of a material highly resistant to destruction when subjected

to high temperatures, such as that of the stream of molten mineral wool forming material. Suitably, steel or an alloy of steel may be employed for the plates. Plates 44 are secured preferably by welding, as indicated at 46, to the main body member. The plates at the forward face of the nozzle are spaced from the casting to define orifices 48. The forward edges of the plates are in planes gradually diverging from the plane of the nozzle face, as shown particularly in Figs. 12, 13, and 14, to define shoulders 50 of gradually increasing height as extensions of the outer walls of the orifice forming slots, similarly as the shoulders 32 of the previously described form. The orifices may be closed at their upper ends as by shims 52. Plates 44 adjacent their lower ends are welded together and to the front and back faces of the main body portion as by welds 54. In this form of the invention, perforations 55 are formed below and substantially in alignment with the orifices to, in effect, extend the streams of fluid issuing from the orifices 48. Plates 44 may be rounded adjacent their forward edges, as indicated at 56 (see Figs. 13 and 14), and cut away, as indicated at 58, to promote the movement of air through the V between the wings.

The operation of the modified form of nozzle is substantially the same as of the previously described embodiment. In this form, however, additional advantages are achieved in that the nozzle may be more readily manufactured and also has a longer life due to the use of the heat-resistant material for the plates 44.

Having thus described our invention in rather full detail, it will be understood that these details need not be strictly adhered to, but that various changes and modifications will suggest themselves to one skilled in the art, all falling within the scope of the invention as defined by the subjoined claims.

What we claim is:

1. A nozzle for projecting a fluid jet against a stream of molten material, said nozzle comprising a hollow body including wings defining an open space therebetween, each of said wings including a forward face exposing an elongated fluid discharge orifice communicating with said hollow interior, said orifices diverging to form a substantially V-shaped port, a portion of each face interiorly of said V and contiguous to an orifice lying in a plane gradually inwardly diverging from the plane of the face portion on the opposite side of said orifice, said last-named divergence beginning at a point adjacent the lower end of said V.

2. A nozzle for projecting a fluid jet against a stream of molten material, comprising a hollow body including wings defining an open space therebetween, each of said wings including a face to lie adjacent and substantially parallel to said stream, said faces exposing elongated fluid discharge orifices in communication with the interior of said hollow body and diverging in substantially a V-formation, the portion of said faces lying interiorly of said V and contiguous to said orifices being gradually relieved with respect to the portions of said faces lying exteriorly of said V and contiguous to said orifices.

3. A nozzle for projecting a fluid jet against a stream of molten material, said nozzle comprising a hollow body including wings defining an open space therebetween, each of said wings including a forward face exposing an elongated fluid discharge orifice in communication with said hollow interior, said orifices diverging upwardly

and including walls one of which projects beyond the other, the walls being constructed and arranged to discharge fluid in jets whose main force converges substantially on a line parallel to said face and spaced therefrom.

4. A nozzle for projecting a fluid jet against a stream of molten material, said nozzle comprising a hollow body including wings defining an open space therebetween, said wings including forward faces having elongated, upwardly diverging, fluid discharge orifices in communication with said hollow interior, and abutments in alignment with, and forming an extension of, the outer edges of said orifices, said abutments tapering relatively to the normal plane of said faces from a minimum height adjacent the lower ends of said orifices to a maximum height adjacent the upper edges thereof.

5. A nozzle for projecting a fluid jet against a stream of molten material, said nozzle comprising a hollow body including upwardly extending hollow wings, the adjacent walls of which define a substantially V-shaped open space, each of said wings including a forward face having an elongated fluid discharge orifice in substantial parallelism with the adjacent wall of said V and in communication with said hollow interior, and abutments in alignment with, and forming an extension of, the outer edges of said orifices, said abutments tapering relatively to the normal plane of said faces from a minimum height adjacent the lower ends of said orifices to a greater height adjacent the upper ends thereof.

6. A nozzle for projecting a fluid jet against a stream of molten material, said nozzle comprising a hollow, integrally cast body including hollow wings, the adjacent walls of which define a substantially V-shaped open space, each of said wings including a forward face having an elongated fluid discharge orifice in substantial parallelism with the adjacent wall of said V and in communication with said hollow interior, and abutments in alignment with, and forming an extension of, the outer edges of said orifices, said abutments tapering relatively to the normal plane of said faces from a minimum height adjacent the lower ends of said orifices to a greater height adjacent the upper ends thereof.

7. A nozzle for projecting a fluid jet against a stream of molten material, said nozzle comprising a hollow body including opposed wings defining an open space therebetween, plates of a heat-resistant material forming the adjacent walls of said wings and defining with the forward edges thereof elongated fluid discharge orifices, the forward edges of said plates being relieved from a point of substantial coincidence with the outer edges of said walls adjacent the bottom of

said orifices to define shoulders in alignment with, and forming an extension of, the outer walls of said orifices, the shoulders upwardly diverging relatively to the forward edges of said plates.

5 8. A nozzle for projecting a fluid jet against a stream of molten material, said nozzle comprising a hollow body including opposed wings defining an open space therebetween, plates of a heat-resistant material forming the adjacent walls of said wings and secured to said hollow body and spaced from the forward edges thereof to define elongated fluid discharge orifices, means closing said orifices adjacent the upper ends of 10 said wings, the forward edges of said plates being located to define shoulders in alignment with, and forming an extension of, the outer walls of said orifices, the shoulders upwardly diverging relatively to the forward edges of said plates.

15 9. A mineral wool forming apparatus comprising means for melting mineral wool forming material and discharging the same in the form of a stream, and a nozzle for projecting a fluid jet against said stream, said nozzle comprising a hollow body including wings defining an open space therebetween each of said wings having a forward face exposing elongated fluid discharge orifices in communication with said hollow interior, said orifices diverging upwardly and including walls one of which projects beyond the 20 other, the walls being constructed and arranged to discharge fluid in jets whose main force converges substantially on a line parallel to said face and spaced therefrom, said nozzle being so arranged relatively to said stream that the stream falls between said orifices and adjacent and substantially parallel to one of said orifices.

30 10. A mineral wool forming apparatus comprising means for melting mineral wool forming material and discharging the same in the form of a stream, and a nozzle for projecting a fluid jet against said stream, said nozzle comprising a hollow body including wings defining an open space therebetween, said wings including forward faces having elongated, upwardly diverging, fluid discharge orifices in communication with said hollow interior, and abutments in alignment with, and forming an extension of, the outer edges of 35 said orifices, said abutments tapering relatively to the manual plane of said faces from a minimum height adjacent the lower ends of said orifices to a greater height adjacent the upper edges thereof, said nozzle being so arranged relatively to said stream that the stream falls between said orifices and adjacent and substantially parallel to one of said orifices.
